UNITED STATES PATENT OFFICE.

ANDREW D. DOWD, OF HOBOKEN, NEW JERSEY, ASSIGNOR TO WESTERN ELECTRIC COMPANY, INCORPORATED, OF NEW YORK, N. Y., A CORPORATION OF NEW YORK.

PRINTING TELEGRAPHY.

Application filed September 23, 1922. Serial No. 589,975.

This invention relates to printing telegraph systems.

The present form of commercial multiplex system is operated in accordance with the 5 Baudot or five unit code which is arranged for the transmitting or receiving of five impulses while the start-stop system required seven impulses. It is often desired to utilize a receiving printer designed for the latter 10 type of system in connection with the former type of system, but to do so requires the use of a device which will provide two additional impulses. It is the object of the present invention to facilitate the operation 15 of a system employing both multiplex and start-stop equipment in a simple and practical manner.

The present invention accomplishes the above object through the provision of a distributor of the start-stop type which is released from the synchronous multiplex distributor and which functions to distribute to a receiving printer designed for seven impulses, the impulses stored in electrical storage elements, as distributed by the multiplex distributor, in addition to supplying the additional impulses required for operating the receiving printer.

One of the embodiments of the invention 30 is illustrated in the accompanying drawing, which shows only so much of the mechanism and circuit connections as are necessary for a clear understanding of the invention.

In the accompanying drawing, A and B 35 are two distributor faces, which faces consist of a plurality of segments and continuous rings. The distributor A is of the continuously operating or synchronous multiplex type, while the distributor B is of the start-stop type, that is, the brush arm which 40 bridges the segments forming the outer ring with the inner ring, is stopped once per revolution. The distributor brush arms 10 and 50 are mounted on a constantly rotating shaft 45 which may be driven by any suitable means, as a driving motor, the brush arm 50 being frictionally mounted on its respective shaft in order that it may be stopped periodically. Each of the brush arms carries brushes which 50 are adapted to sweep over its respective distributor face, thus interconnecting the segments and the continuous rings as the brush arms are rotated.

Connected intermediate the distributor 55 faces A and B are a plurality of condensers

or other form of electrostatic means 11 to 15, inclusive. These condensers have one terminal grounded, while the other terminal is connected with a segment forming a part of the outer ring of the distributor face A, 60 and are included in one channel of the multiplex distributor, which, as is well known to those familiar with such systems, may be provided for double duplex operation. As the brush arm 10 revolves, the segments to 65 which the terminals of the condensers 11 to 15, inclusive, are connected, will be bridged by means of brush 16 with continuous ring 17 to which the armature of line relay 18 is connected. Line relay 18 has its windings 70 serially connected with line conductor 19, which extends from a distant station and over which groups of code combinations of 75 message impulses are transmitted, and which are, through the instrumentalities of the mechanism hereinafter described, recorded in printed form. The impulses transmitted over the line conductor 19 are preferably of the Baudot or five-unit code. As brush arm 10 bridges the respective segments condensers 11 to 15, inclusive, will be charged in 80 accordance with the operation of relay 18, thereby storing a group of impulses corresponding to the impulses originally transmitted over the line conductor 19.

Each of the condensers 11 to 15 also has its ungrounded terminal connected with segments forming a part of the outer ring of the intermittently operating distributor B. This distributor is provided with a release 85 magnet 54, the energization of which is controlled through segment 21 forming a part of the multiplex distributor A. The energizing circuit of the release magnet 54 is completed at a time following the passage 90 of brush 16 carried by the distributor brush arm 10 over segment 24, to which the first of the series of condensers is connected.

Upon the release of the brush arm 50, brush 51 carried thereby sweeps over the segments connected to one terminal of the condensers 11 to 15, and impresses on a relay 55 impulses in accordance with those stored in these condensers and as originally transmitted over the line conductor 19. Relay 55 controls, through its contacts, a selecting magnet 56 comprising a pair of operating coils 57 and 58 and a movable armature 59.

Selecting magnet 56 forms a part of the printer unit C, which in the preferred form 110

of the invention consists of a plurality of rotatable shafts, which are arranged, upon the operation of release latches, to be rotated through an angle equal to 180° . Such 5 shafts in rotating impart a characteristic rotative motion to a type wheel 23 through a series of links and connecting levers. For a more complete description and disclosure of such a printing unit reference may be had to 10 application, Serial No. 531,337, filed January 24, 1922. Inasmuch as the printer mechanism per se does not form a part of the present invention, so much of the mechanism has been shown as is considered necessary for 15 a clear understanding of the present invention.

In the form of the invention disclosed, the distributor mechanism forming a part of the printer unit is the mechanism which selects 20 in this particular case the series of shafts for rotation, and start-stop distributor B, which, as previously described, is made up of a series of concentrically arranged rings over which a brush arm is arranged to sweep, are 25 driven from a common motor. Obviously, however, separate driving means may be provided for the respective parts by employing friction clutches for giving the proper driving connections.

30 The operation of the system for the selecting and printing of a character is as follows: Assume that it is desired to select and record the character J, and that such character in accordance with the Baudot five-unit 35 code comprises the following selecting units: positive, positive, negative, positive, and negative. For this group of impulses, the transmitting mechanism (not shown) at the station connected by the line conductor 19, 40 is operated to impress impulses corresponding to the above group. Line relay 18 thereupon responds to such changes in line conditions, for causing the corresponding charging 45 of condensers 11 to 15 inclusive. Upon the passage of brush 16 over segment 24, relay 18 being operated to close contact 29, condenser 11 is charged positively over a circuit extending from battery, contact 29, ring 17, brush 16, segment 24, and condenser 50 11, to ground. Condenser 11 is thereupon charged in accordance with the first impulse forming the group of code combinations representing the character J. Likewise, as brush 16 passes over segment 25, condenser 55 12 will be charged positively. The next selecting unit being a negative impulse, line relay 18 is caused to reverse the position of its armature, thereby opening contact 29 and closing contact 32. Now, upon the passage 60 of the brush 16 over segment 26, condenser 13 will be charged negatively as a charging circuit of this character is completed at this time. For the other two selecting units condenser 14 will be charged in a manner similar to condensers 11 and 12, but condenser

15 will be charged as condenser 13, as a condition similar to that described in connection with the condenser 13 exists upon the passage of brush 16 over segment 28, to which this particular condenser is connected.

70 Following the passage of the brush 16 on to segment 24, brush 33 carried by the brush arm 10 of distributor A, passes over segment 21, bridging this segment with ring 34. Upon the bridging of segment 21 with ring 75 34, a circuit is completed for causing the energization of release magnet 54, which in energizing withdraws the release latch holding distributor arm 50 against rotation. Distributor arm 50 is thereupon free to rotate due to power being communicated thereto through a series of shafts, gears, and friction clutches. Immediately upon the passage of brush 51 off of segment 35 and on to segment 36, relay 55 is energized for reversing 80 the position of its armature. The reversal of the position of the armature of relay 55 completes an energizing circuit for coil 58 of selecting magnet 56. Coil 58 of this magnet upon being energized attracts 85 the armature 59 to the right for causing the release of the mechanism to which a series of tripping fingers 37, 38, 39, 40, 41, and 42 are connected. This release mechanism comprises a latch 43 arranged in the path of 90 travel of armature 59 so that upon the energization of coil 58, latch 43 is operated for causing the operation of a pivoted lever 45, which moves a stop member out of the path of arm 46, which is secured to the mechanism controlling the rotation of tripping fingers 37 to 42, inclusive. For the particular selection chosen, condensers 11, 12, and 14 are charged positively, while the other condensers possess a negative charge. Thus, 95 as brush 51 passes over the segments to which these condensers are connected, relay 55 will accordingly be caused to reverse the position of its armature for causing a corresponding condition to exist in the selecting magnet 56. As for example, upon the passage of brush 51 on to segment 52, a discharge circuit for condenser 11 is established 100 over a circuit extending from one terminal of condenser 11, segment 52, brush 51, ring 53, conductor 60, and the windings of relay 55, to ground. This relay is caused to move its armature in accordance with the charge 105 of this condenser. In order that the impulses stored in the condensers 11 to 15 will be transferred at the proper moment, the rods to which the release latches are secured and the shaft carrying brush arm 50 rotate at substantially the same speed. Selecting magnet 56, upon being energized, positions 110 the corresponding tripping fingers with respect to one or the other of the release latches, depending upon the character of 115 impulse stored in the condensers 11 to 15, as described in the previously mentioned ap- 120 125 130

application. Due to the energization of selecting magnet 56 in accordance with the impulses stored in the condensers 11 to 15, inclusive, tripping fingers 37 to 42 will be positioned in accordance with the group of impulses transmitted for the particular character to be recorded. As these tripping fingers revolve, they operate the latches controlling the rotation of a shaft individual to 10 a pair of such latches. To these shafts there is connected a series of connecting links, which in turn are connected to a rack 47 by means of a common link, the teeth of which engage the teeth of a gear wheel 48. This 15 gear wheel 48 is rigidly secured to type wheel 23 so that upon the rotation of the shafts, which are normally held against rotation by the release latches, the cumulative effect produced by such rotation will cause 20 a corresponding rotation of the type wheel 23 for bringing the desired character into printing position. The printing of the character is accomplished as in the previously mentioned application.

25 Following the passage of brush 33 off of segment 21 of the distributor A, the energizing circuit of release magnet 54 is broken so that the brush arm 50 will be stopped after having completed its cycle of rotation.

By providing a series of condensers which are operated in accordance with the impulses received on the multiplex distributor and transfer mechanism operative to cause the operation of the selecting mechanism, as determined by the character of the impulses stored in such condensers, a printer is given considerably more time within to operate than if it were connected directly to the multiplex distributor. 30

35 The invention claimed is:

40 In combination, a line, a multiplex distributor connected to said line, a plurality of condensers associated with said distributor and arranged to be charged in accordance with predetermined combinations of impulses distributed thereto by said distributor from said line, a printing type wheel, a system of levers arranged to rotate said wheel in both directions to desired positions, a series of rotatable shafts for actuating said levers, an electromagnet for releasing said shafts in predetermined combinations, and a start-stop distributor for successively connecting said condensers to said electromagnet. 45

50 In witness whereof, I hereunto subscribe my name this 22nd day of Sept., A. D. 1922.

55 ANDREW D. DOWD.
